UNITED STATES PATENT OFFICE.

ELLES R. CARHUFF, OF NEWARK, NEW JERSEY.

APPARATUS FOR THE MANUFACTURE OF PRUSSIATE OF POTASH.

SPECIFICATION forming part of Letters Patent No. 310,376, dated January 6, 1885.

Application filed October 9, 1883. (No model.)

To all whom it may concern:

Be it known that I, ELLES R. CARHUFF, a citizen of the United States, residing at Newark, in the county of Essex and State of New Jersey, have invented certain new and useful improvements in Apparatus for the Manufacture of Prussiate of Potash; and I do hereby declare the following to be a full, clear, and exact description of the invention, such as will 10 enable others skilled in the art to which it appertains to make and use the same, reference being had to the accompanying drawings, and to letters of reference marked thereon, which form a part of this specification.

15 The object of this invention is to simplify and make more effectual the apparatus employed in the manufacture of prussiate of potash; and it consists of such arrangement, construction, and operation of the various parts 20 as will be hereinafter set forth and claimed.

In the drawings, Figure 1 is a transverse section of a furnace with a side elevation of a retort or "plot" arranged therein. Fig. 2 is a front elevation of the mouth of the retort 25 and part of the furnace. Fig. 3 is a top view of the clutch at the rear of the furnace. Fig. 4 is a section through line x of Fig. 3, and Fig. 5 is a section through line x' of Fig. 1.

Similar letters of reference indicate like 30 parts in each of the several figures.

Referring to the drawings, A is the retort, made of cast-iron, the form of which is elliptical, but may be circular, if desirable, provided with an opening, B, in the neck thereof, and 35 an elongated end, C, formed substantially as shown, having a lug or feather, c' . Within the retort are curved ledges or ribs a , formed similar to an S, preferably four in number, and placed equidistantly apart. Between the 40 curved ribs a are straight ribs a' .

D is a coupling, by which the end C of the retort is firmly connected with the shaft E, which turns in the bearing e , and having attached thereto a cog-wheel, F, or other suitable gearing for rotating the retort. The coupling D is composed of the parts d , d' , and d'' , Figs. 1, 3, and 4, held together by bolts, as shown. The part d has a recess, c^2 , therein to receive the lug c' , as shown in Fig. 4, by 45 which the retort is prevented from moving longitudinally or laterally independent of the

coupling and shaft. The end of the shaft E extends into the coupling, as shown in Fig. 4, having a hole in said end to receive a bolt, e' , which passes through both coupling and shaft 55 and prevents the withdrawing of the shaft. The other end of the retort rests upon a friction-roller, G, secured to a shaft, g , working in suitable bearings, as shown in Fig. 1. Rising on each side of the mouth of the retort 60 are arms H, having gibs or supporting-pieces i near their upper extremity, Fig. 2, which bear against the sides of the mouth, supporting the same, said gibs being adjustable by means of the screws i' and i'' . The retort is 65 inclined toward the rear of the furnace, as indicated in Fig. 1, so as to prevent the contents of said retort from falling out or collecting at the mouth while revolving within the furnace. The retorts receive their motion through the 70 gearing at the rear of the furnace, the points of bearing being without the same, and placed at a suitable distance therefrom to avoid the intense heat thereof, especially the bearing and coupling at the rear, as indicated in Fig. 75 1. The mouth of the retorts may be closed by a door suitably hung, as will be readily understood.

The furnaces in which the retorts are placed may be larger or smaller, according to the 80 number of retorts therein, preferably containing three, the furnaces being arranged back to back, with the gearing of the retorts so placed that they may be rotated by a single shaft provided with gearing, or in any suitable manner. 85

The roof of the furnace is constructed as shown in Fig. 1, consisting of an arch of masonry, fire-brick preferred, the ends of said arch resting upon iron angle-plates j , Figs. 1 and 2, and provided at intervals with braces or 90 stays k , either cast integral with the iron angle-plates or bolted thereto, a small space being left between the arch and the stays to allow for expansion of the masonry.

In order that the retorts may be removed 95 from the furnace when unfit for use without tearing down the furnace, I divide the roof into several parts, preferably three, corresponding to the number of retorts, with two or more braces, k , to each division, said braces 100 being provided with eyebolts l , Fig. 1, the divisions being made transversely from front to

rear through the masonry and iron plates. The arch resting upon the iron angle-plates, the stays being secured to said plate, the parts may be lifted off of the walls by tackle attached to the eyebolts, and replaced without disturbing or injuring the furnace, the convenience and economy of which are evident.

In order to thoroughly mix the charge in the retort, so that it may be sufficiently subjected to the heat, I employ ribs *a a'*, cast on the inner surface of the retort, which form ledges, upon which the contents of the retort collect, and, being thrown off while the retort is revolving, become thoroughly mixed and fused. By having the ribs curved, as shown, Fig. 1, while the retort is turning in the direction indicated by the arrows on Fig. 2, the contents or charge is pushed or thrown toward the rear of the retort, thereby still further preventing the charge from collecting at or falling out of the mouth of the retort. Moreover curved ribs are much more durable, because stronger, than straight ribs, as is evident. The friction and consequent wear is greatly reduced by employing but a single bearing-point at each end of the retort instead of two or more, as heretofore used.

Having thus described my invention, what I claim is—

- 30 1. A retort, A, provided with a hollow neck, an elongated end, C, having thereon a feather, as *c*, for the purpose herein set forth, and having within S-shaped ribs.
2. In combination, a retort, A, having on the elongated end thereof a lug, *c*, shaft E, coupling D, friction-roller G, and means for supporting the end of the retort, which turns on said friction-roller, all substantially as set forth.
- 35 3. In combination, a retort, A, shaft E, coupling D, friction-roller G, arms H, and adjustable gibs *i*, all as set forth.
- 40 4. A retort, A, adapted to be used in the manufacture of prussiate of potash, having

within curved ribs, as *a*, said curves being approximately S-shaped, all substantially as and for the purposes set forth.

5 5. A retort, as A, having within S-shaped ribs, as *a*, and straight ribs *a'*, all substantially as and for the purposes set forth. 50

6. In combination, a furnace adapted to be used in the manufacture of prussiate of potash, having a removable roof, a retort, A, arranged and adapted to rotate within said furnace, a friction-roller, G, a coupling device, as 55 D, and driving-gear, all substantially as set forth.

7. In combination, a furnace adapted to be used in the manufacture of prussiate of potash, a retort, A, friction-roller G, means for supporting the end of the retort bearing on said friction-roller, a coupling device, D, and driving-gear, said retort rotating on a single bearing-point at each end thereof, placed outside of the furnace. 65

8. A retort adapted to be used in the manufacture of prussiate of potash, the body of which is arranged within a furnace, one end bearing upon one or more friction-rollers, the other end being coupled with a shaft turning 70 in a bearing, said shaft being provided with gearing, or otherwise adapted to receive motion from a driving-shaft with both the bearings outside of the furnace.

9. A retort approximately spherical, adapted to be used in the manufacture of prussiate of potash, having a non-perforated shell, and provided with elongated ends, one of which has an opening therethrough, substantially as and for the purposes herein set forth. 75

In testimony that I claim the foregoing I have hereunto set my hand this 8th day of October, 1883.

ELLES R. CARHUFF.
